US0D1105593S

(12) **United States Design Patent** (10) Patent No.: **US D1,105,593 S**
(45) Date of Patent: ** Dec. 9, 2025

(54) **ATOMIZATION CORE FOR AN ELECTRONIC CIGARETTE**

(71) Applicant: **Aspire North America LLC**, Venice, CA (US)

(72) Inventor: **Michael Wang**, Redondo Beach, CA (US)

(73) Assignee: **Aspire North America LLC**, Venice, CA (US)

(**) Term: **15 Years**

(21) Appl. No.: **35/002,347**

(22) Filed: **Apr. 18, 2023**

(80) **Hague Agreement Data**

Int. Filing Date: **Apr. 18, 2023**

Int. Reg. No.: **DM/238042**

Int. Reg. Date: **Apr. 18, 2023**

Int. Reg. Pub. Date: **Jun. 28, 2024**

(51) **LOC (15) Cl.** 27-02

(52) **U.S. Cl.**

USPC **D27/162**

(57) **CLAIM**

The ornamental design for an atomization core for an electronic cigarette as shown and described.

DESCRIPTION

1. Atomization core for an electronic cigarette

1.1 : Perspective

1.2 : Perspective

1.3 : Right side elevation

1.4 : Front

1.5 : Left side elevation

1.6 : Rear

1.7 : Top

1.8 : Bottom

The broken lines in the drawings depict portions of the atomization core for an electronic cigarette that form no part of the claimed design.
